UNITED STATES PATENT OFFICE

153,967

DESIGN FOR A PORTABLE BATTERY
CHARGER

Lewis A. Medlar, Oreland, Pa., assignor to Fox
Products Company, Philadelphia, Pa., a cor-
poration of Pennsylvania

Application April 21, 1948, Serial No. 145,877

Term of patent 14 years

(Cl. D26—5)

To all whom it may concern:

Be it known that I, Lewis A. Medlar, a citizen of the United States, residing in Oreland, in the county of Montgomery and State of Pennsylvania, have invented a new, original, and ornamental Design for a Portable Battery Charger, of which the following is a specification, reference being had to the accompanying drawing, forming part thereof.

Fig. 1 is a perspective view of a portable battery charger, showing the front and one side of my new design;

Fig. 2 is a perspective view of the same showing the front and other side thereof;

Fig. 3 is a side elevation thereof; and

Fig. 4 is a rear elevation thereof.

The important and characteristic features of

my design reside in the portions shown in full lines in the drawing.

I claim:

The ornamental design for a portable battery charger, substantially as shown and described.

LEWIS A. MEDLAR.
